PUTLOG

Filed March 5, 1929

Inventor

Thomas H. Kingston

By *Chas. Williamson*
Attorney

UNITED STATES PATENT OFFICE

THOMAS HAVELOCK KINGSTON, OF WEST SOMERVILLE, MASSACHUSETTS, ASSIGNOR TO BUILDERS' PATENT SCAFFOLDING COMPANY, A PARTNERSHIP COMPOSED OF FRANK G. KINGSTON, A. R. KINGSTON, C. C. PIMM, AND MABEL G. KITCHEN, OF WEST SOMERVILLE, MASSACHUSETTS

PUTLOG

Application filed March 5, 1929. Serial No. 344,503.

My invention relates to scaffolding or staging for workmen engaged in erecting brick and masonry walls and in particular to the horizontal supports known as putlogs which have devices at one end for detachable connection with the wall being erected, and at the other end rests upon horizontal supports that are secured to the vertical poles or directly to the poles. These putlogs consist of two parts or members, one that includes a comparatively thin blade-like metal member that extends horizontally through a joint between adjacent bricks or stones and has a bearing upon the top of the under brick or stone, and the other a bar made usually most readily and conveniently of wood. An acceptable putlog must combine the properties of efficient anchorage or bearing connection with the wall, facility of application to and removal from the wall and that without damage to the latter on the front or exposed face, adequate strength because human life and limb are concerned, the minimum of cost, and such connection between the wall engaging member and the other member that they may be readily assembled for use even by unskilled labor so that the complete putlog need not be put up at and sent out from the factory, but may be provided at some remote place from the factory and thus cost of shipment or transportation be greatly reduced as by the shipment of the wall-engaging member alone. I have had in view all of the considerations just mentioned in producing my invention and in what I regard as its best and most satisfactory form all of them are embodied therein, but it is to be understood that forms or embodiments of my invention may be employed in which less than all of the qualities or properties just mentioned will be found.

My invention consists in whatever is described by or is included within the terms or scope of the appended claims.

In the drawings:

Fig. 1 is a perspective view of a putlog embodying my invention, which requires no wood bar;

Fig. 2 is a similar view of another embodiment

of my invention adapted for use with a bar or body of wood;

Fig. 3 is a perspective view of yet another embodiment of my invention for use with a bar or body of iron tubing or pipe.

Describing briefly a putlog embodying my invention, it includes the two essential parts of a comparatively thin bar which in use is thrust in the joint or space between adjacent bricks provided by omitting mortar between the bricks for the purpose, and the body member which extends outward from the wall and constitutes the horizontal support for the planking that forms the platform for the workmen and which at the outer end rests upon or is supported by the horizontal ledger board.

Describing in detail what is shown in the drawings, the anchoring or wall-engaging member is a flat metal bar that is blade-like which has a bearing portion, 10, of sufficient length to extend between adjacent bricks of a course, so that a downwardly extending hook, 11, at the free end may catch over the upper rear corner of the underlying brick. As shown in Fig. 1, this brick-engaging portion, 10, is the continuation in a straight line of a thin metal bar, 12, of sufficient length to reach to the ledger boards and together with an angle bar, 13, riveted to each side and of the same length constitutes the putlog body, the angles, 13, being both reinforcing members and by having the horizontal flange uppermost providing a wide bearing or support for platform planks laid thereon.

In the event that additional strength may be required, I provide a loop or stirrup, 14, near or at each end of the angles 13, and projecting from the upper side thereof for the detachable connection of a wood log or body, 15, shown in dotted lines in Fig. 1. The end location of the loops or stirrups, 14, obviously hinders in no way the use of the putlog without the wood body, 15, because the planks forming the scaffolding platform may be laid on the tops of the bar, 12, and angles, 13, in the space between the loops, 14.

The loops or stirrups, 14, may each be an inverted U-shape strap with its legs joined at the bottom by a cross bar, 16, whose

ends project through holes in the legs and are offset or riveted thereto and through which strap, 16, rivets, 17 pass through the horizontal flanges of the angles, 13, below.

5 The embodiment of my invention shown in Fig. 2 is the same in all essential respects, as that shown in Fig. 1 with the exception that the bar, 12, and angles, 13, are not extended to form the putlog body, but they 10 are made only long enough for the attachment thereto of two loops, 14, corresponding to the loops, 14, of Fig. 1 for the reception of the end portion of a wood body 15, it being possible in this case to use only a wood 15 body as the platform planks support.

The form of my invention shown in Fig. 3 is the same in all essential respects as that shown in Fig. 2, including the clincher member, 10, with the hook, 11, the short angles 20 13, riveted to a short extension or shank of the clincher member and two loops, 140, but the loops, 140 instead of being rectangular or flatsided are substantially semi-circular, so that they may readily receive the end portion 25 of a piece of round pipe or tubing that serves as the body member to receive and support the scaffolding platform.

Means may be provided to prevent the accidental separation of the pipe or tube when 30 used with the stirrups or loops of the construction shown in Fig. 3. Such means may be a pin or bolt, 18, that passes through alining holes in the side legs of one of the loops and through a registering hole extending diametrically through the inserted portion 35 of the pipe or tube. Such an attaching means is readily applied, is certain in its action and may be readily removed for taking a putlog apart.

40 Of course, the great stresses which putlogs are subjected to are bending and shearing stresses, and it will, therefore, be evident that with the angles riveted with their side flanges to the interposed bar or plate, great 45 resistance to such stresses is afforded.

What I claim is:

1. A putlog comprising a wall-engaging member of metal and a body comprising angles secured to opposite sides thereof with 50 horizontal flanges at the top that provide extended staging-supporting surfaces.

2. A putlog comprising a wall-engaging member of metal and a body comprising angles secured to opposite sides thereof with 55 horizontal flanges at the top that provide extended staging-supporting surfaces, and stirrups secured upon said horizontal flanges.

3. A putlog comprising a wall-engaging member of metal and angles secured to opposite sides thereof with horizontal flanges at the top, and a stirrup or stirrups having a cross bar resting on the flanges and secured to the flanges.

4. A putlog comprising a wall-engaging member of metal with flat vertical sides,

angles with vertical flanges engaging the vertical sides of said member and with horizontal flanges uppermost and stirrups spaced apart longitudinally of the putlog secured to said horizontal flanges.

5. A putlog comprising a body of a length 70 to reach from a wall to pole-supported ledger boards and a thin metal bar with vertical sides lying between opposite longitudinally extending portions of said body, said thin metal bar projecting at the wall end of the 75 body and the projecting portion constituting a member insertable in a space between adjacent bricks of the wall.

6. A putlog comprising a body member of 80 a length to reach from a wall to a pole-supported ledger board and a thin metal bar with vertical sides situated at the bottom and extending parallel with the body, said thin metal bar projecting at the wall end of 85 the body and the projecting portion constituting a member insertable in a space between adjacent bricks of the wall, the remainder of said thin metal bar fitting between and engaged on opposite sides by 90 longitudinally extending portions of the body at the bottom thereof, fastening means passing horizontally through said metal bar and the body portions embracing the same at the sides and a stirrup with vertical and 95 horizontal portions that overlie and engage adjacent sides of the body at the end from which the wall-engaging portion of said thin metal bar projects.

In testimony whereof I hereunto affix my 100 signature.

THOMAS HAVELOCK KINGSTON.
